UNITED STATES PATENT OFFICE.

PERLIE A. DYAR, OF BOSTON, MASSACHUSETTS.

WASTE-RECEPTACLE.

1,100,423.

Specification of Letters Patent. Patented June 16, 1914.

Application filed April 28, 1913. Serial No. 763,977.

To all whom it may concern:

Be it known that I, PERLIE A. DYAR, a citizen of the United States, and a resident of Boston, in the county of Suffolk and State 5 of Massachusetts, have invented certain new and useful Improvements in Waste-Receptacles, of which the following is a specification.

This invention relates to receptacles located in public places to receive waste paper and other debris, the receptacle being adapted to be supported in a position elevated above the ground and to receive the waste at its upper portion and discharge the same 15 at its lower end.

The invention has for its object to provide an improved closure for the lower end of the receptacle adapted to be firmly retained in position to support the contents of the 20 receptacle and to be readily released to permit the discharge of the contents.

The invention consists in the improvements which I will now proceed to describe and claim.

25 Of the accompanying drawings:—Figure 1 represents a perspective view of the waste receptacle embodying my invention. Fig. 2 represents a side elevation of the same mounted on a support, the bottom being 30 closed. Fig. 3 represents a view similar to Fig. 2, showing the bottom open. Fig. 4 represents the section of line 4—4 of Fig. 1.

The same reference characters indicate the same parts in all the figures.

35 My improved receptacle comprises a body 12 preferably made chiefly of sheet metal and adapted to be secured to a vertical support such as a post 13. The body has a receiving opening 14 in its upper portion 40 and is open at its lower end. 15 represents a bottom piece hinged at 16 to one side of the lower end of the body and formed to close said lower end, the bottom piece being of smaller area than the cross sectional area 45 of the interior of the body, and adapted to swing upwardly into the interior of the body as indicated by dotted lines in Fig. 4 for a purpose hereinafter stated.

The bottom piece is provided with a U- 50 shaped locking member 17 projecting downwardly from its under side, said member having a recess one end of which is closed and constitutes a stop. To opposite sides of the body is pivoted a wire bail composed

of end portions 18 having ears or trunnions 55 19 journaled in orifices formed in the sides of the body, and an intermediate portion 20 adapted to extend across the open end of the body, and to engage the locking member 17 and support the bottom piece. The 60 bail is adapted to be swung outwardly to the right hand dotted line position shown by Fig. 4 to remove the portion 20 from a position under the bottom piece and permit the bottom piece to be swung downwardly 65 as shown by Fig. 3 to release the contents of the receptacle. Before doing this, the bail is swung inwardly to the left hand dotted line position, Fig. 4, and the bottom piece is raised as shown by dotted lines, so 70 that the portion 20 may be moved outwardly under the locking member 17. To again secure the bottom piece, it is first raised to the dotted line position and the bail is swung inwardly to the left hand dotted line position. The bottom is then allowed to drop until it rests on the portion 20, the latter being then moved to the intermediate position shown by Fig. 4 until it is arrested by the stop formed by the closed end of the 80 locking member. The bottom is now securely supported against any possibility of accidental displacement. The bottom piece and bail constitute a simple and efficient closure for the bottom of the receptacle, presenting no projections on the exposed vertical portions of the receptacle and being therefore free from liability to engage and tear garments of people passing the receptacle. 90

What I claim and desire to secure by Letters Patent is:—

A waste receptacle comprising a body which is open at its lower end and has a receiving opening at its upper portion, a 95 bottom of smaller area than the internal cross sectional area of the body, hinged to the lower end of the rear side of the body and having a U-shaped locking member on its under side forming a recess with a 100 closed end, and a supporting bail having end portions pivotally connected to opposite sides of the body and an intermediate portion adapted to extend across the open end of the body to support the bottom in its 105 operative position and also adapted to swing outwardly from the front side of the body to release the bottom, the bottom being mov-

able upwardly into the body to permit the bail to swing inwardly across the locking member prior to engagement therewith, and the closed end of the locking member forming a stop which prevents the bail from swinging forward to release the bottom when the latter is in its operative position.

In testimony whereof I have affixed my signature, in presence of two witnesses.

PERLIE A. DYAR.
